UNITED STATES PATENT OFFICE.

MICHAEL LOFTUS, OF CHICAGO, ILLINOIS.

NON-REFILLABLE BOTTLE.

No. 824,035.

Specification of Letters Patent.

Patented June 19, 1906.

Application filed September 5, 1905. Serial No. 277,040.

To all whom it may concern:

Be it known that I, MICHAEL LOFTUS, a citizen of the United States, residing at Chicago, in the county of Cook and State of Illinois, have invented new and useful Improvements in Non-Refillable Bottles, of which the following is a specification.

This invention is a device which is applicable to bottles to prevent the refilling thereof, the principal feature being a ball-valve having a stem extending to the lower part of the bottle, a suitable guideway being provided for the same at the bottom. In the neck of the bottle is a glass retainer or guard for the valve.

In the drawings, Figure 1 is a central vertical section of a bottle embodying my improvement. Fig. 2 is a cross-section on the line 2 2 of Fig. 1.

Referring specifically to the drawings, 10 refers to the bottle, which may be of any suitable form or shape. In this bottle in the neck 12 is a valve-seat 11. Fitting this is a ball 12^a, having a pendent rod or stem 13, 25 which extends down through the body of the bottle into a small tubular recess 14 at the bottom of the bottle. This is done to secure more perfect equilibrium and to retain the ball in its position and bring it to its seat at 30 all times, which might not be accomplished if the ball was simply allowed to play loose.

The retainer 15 is a cylindrical piece of glass, which is placed in position after the

ball 12^a has been inserted. This retainer 15 acts as a weight to keep the ball in position, 35 but does not prevent the flow of liquid out of the bottle.

At the mouth of the bottle is a screw-threaded piece of glass or cork 16 screwed and cemented therein. This is not an essential feature of the invention; but it serves to prevent to some extent tampering with the valve.

When the bottle is tipped down to pour therefrom, the ball 12^a and retainer 15 fall 45 away from the valve-seat, and the liquid can flow through. When the bottle is upright, the ball falls to the valve-seat and closes the valve, so that liquid cannot be poured into the bottle.

What I claim as new, and desire to secure by Letters Patent, is—

A bottle having a guide-socket in the bottom and a valve-seat in the neck, a valve-ball fitting the seat and having a stem extending 55 into the socket and movable therein to guide the ball to its seat, and a weight comprising a loose movable piece of material partially filling the space in the neck above the ball.

In testimony whereof I have signed my 60 name to this specification in the presence of two subscribing witnesses.

MICHAEL LOFTUS.
